CLAIM

The ornamental design for a necklace attachment, as shown and described.

DESCRIPTION

FIG. 1 is a perspective view of first embodiment thereof;

FIG. 2 is a front view of first embodiment thereof;

FIG. 3 is a back view of first embodiment thereof;

FIG. 4 is a side view of first embodiment thereof;

FIG. 5 is an end view of first embodiment thereof;

FIG. 6 is a perspective view of second embodiment thereof;

FIG. 7 is a front view of second embodiment thereof;

FIG. 8 is a back view of second embodiment thereof;

FIG. 9 is a side view of second embodiment thereof; and,

FIG. 10 is an end view of second embodiment thereof.

The broken line showing portions of the necklace attachment, in FIGS. 1, 2, 3, 6, 7, and 8 is included for the purpose of illustrating environment and forms no part of the claimed design.
